HYDRAULICALLY OPERATED FEEDING
MECHANISM

Herbert A. Silven, Worcester, Mass., assignor to
Norton Company, Worcester, Mass., a corpora-
tion of Massachusetts

Application November 1, 1946, Serial No. 707,214

8 Claims. (Cl. 51—2)

1

The invention relates to grinding machines and more particularly to a grinding wheel feeding mechanism.

One object of the invention is to provide a simple and thoroughly practical grinding wheel feeding mechanism. Another object of the invention is to provide a hydraulically operated wheel feeding mechanism which is arranged to cause a rapid approaching movement of the grinding wheel, then a slow shoulder grinding feed of the wheel until the grinding wheel engages the peripheral surface of the work at which time the infeed is automatically reduced to a slower uniform body feed. Another object of the invention is to provide a wheel feeding mechanism in which a feeler actuated mechanism automatically changes the rate of infeed when the periphery of the grinding wheel engages the body portion of the work to be ground regardless of the initial diameter of the body portion. Another object of the invention is to provide a wheel feeding mechanism in which the rapid approaching or shoulder feed of the grinding wheel continues until the periphery of the grinding wheel engages the cylindrical body portion of the work at which time the feed is automatically reduced to a predetermined and uniform grinding feed. Another object of the invention is to provide a wheel feeding mechanism with a control means which is governed by the diameter of the work being ground for automatically changing the rate of infeed to a predetermined grinding feed when the grinding wheel engages the periphery of the work piece. Another object of the invention is to provide a hydraulically actuated electrically controlled feeding mechanism in which a work engaging feeler and control means governed thereby automatically changes the rate of feed of the grinding wheel to a grinding feed when the grinding wheel moves into engagement with the work piece being ground. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawings, in which is shown one of various possible embodiments of the mechanical features of this invention,

Fig. 1 is a diagrammatic showing of the hydraulically actuated electrically controlled grinding wheel feeding mechanism.

2

A grinding machine has been illustrated in the drawings comprising a base 9 which supports a transversely movable grinding wheel slide 10 on the usual V-way and flat way (not shown). The wheel slide 10 serves as a support for a rotatable grinding wheel 11. A rotatable work support is provided for rotatably supporting a work piece 12 in order that its peripheral cylindrical surface may be ground. The work support has not been illustrated since it is not considered to be a part of the present invention. A conventional work support comprising a head stock and a footstock may be utilized such as for example that shown in the expired U. S. patent to C. H. Norton, No. 762,838 dated June 14, 1904, to which reference may be had for details of disclosure not contained herein.

The wheel slide 10 is provided with a depending half nut 13 which meshes with or engages a rotatably mounted feed screw 14. The right hand end of the feed screw 14 is supported in a slidably mounted bearing 15. The screw 14 may be rotated by the old and well known manually operable cross feeding mechanism such as for example that shown in the above mentioned expired U. S. patent.

In order to feed the grinding wheel toward and from the work piece, a hydraulically operated mechanism is provided comprising a cylinder 16 which is fixedly mounted in the base 9. The cylinder 16 contains a slidably mounted piston 17 which is connected to a double end piston rod 18. The left hand end of the piston rod 18 is operatively connected to the slidably mounted bearing 15. As illustrated in the drawings, the hydraulic cylinder 16, the piston 17, and the piston rod 18 are arranged in axial alignment with the feed screw 14. When it is desired to move the grinding wheel to a rearward or inoperative position such as that shown in the drawings, fluid under pressure may be admitted through a pipe 19 into a cylinder chamber 20 to cause the piston 17 and associated parts to move toward the right into the position illustrated in the drawing. During this movement of the piston 17, fluid within a cylinder chamber 21 may be exhausted through a pipe 22. Similarly, when it is desired to cause a forward feeding movement of the grinding wheel, fluid under pressure may be admitted through the pipe 22 into cylinder chamber 21 to cause the piston 17 to move toward the left and thus transmit a corresponding movement through piston rod 18, the slidably mounted bearing 15, the feed screw 14, the half nut 13, and the wheel slide

10 to cause the wheel 11 to approach the peripheral surface of the work piece 12. During this movement of the wheel slide 10, fluid within the cylinder chamber 20 may be exhausted through the pipe 19.

A fluid pressure system is provided comprising a reservoir 25. A motor driven pump 26 draws fluid through a pipe 27 from the reservoir 25 and passes fluid under pressure through a pipe 28 to a control valve 29. The control valve 29 is preferably a piston type control valve comprising valve stem 30 having formed integrally therewith a plurality of valve pistons 31, 32, 33 and 34. The valve stem 30 is normally held in its right hand end position by means of a compression spring 35 which surrounds the valve stem 30 and is interposed between the end face of the valve casing 29 and a flange 36 which is either formed integral or fixedly mounted on the valve stem 30. In the position of the valve as shown in the drawings, fluid under pressure passing through the pipe 28 enters a valve chamber located between the valve pistons 32 and 33 and passes out through the pipe 19 into the cylinder chamber 20 to cause the piston 17 to move toward the right into the position illustrated in the drawings. During this movement of the piston 17, fluid within the cylinder chamber 21 may exhaust through the pipe 22 into a valve chamber located between the valve pistons 31 and 32 and pass out through an exhaust pipe 38 into the reservoir 25.

In the preferred construction, the valve 25 is arranged to be automatically shifted into a reverse position to change the direction of flow of fluid under pressure by means of an electric solenoid 37. When the solenoid 37 is energized, in a manner to be hereinafter described, the valve stem 30 will be shifted toward the left against the compression of the spring 35 so that fluid under pressure passing through the pipe 28 will enter the valve chamber located between the valve pistons 32 and 33 and pass outwardly through the pipe 22 into the cylinder chamber 21 to cause an infeeding or approaching movement of the grinding wheel slide 10 and the grinding wheel 11.

In order to control the energization of the solenoid 37, power lines 40 are provided for supplying electrical current to the control system. A push button type starter switch 41 is provided which, when closed, serves to energize a relay switch 45. When the relay switch 45 is energized, a circuit is closed to energize the solenoid 37 and thereby shift the control valve 29 so as to cause a forward feeding movement of the grinding wheel 11. A push button type stop switch 42 is provided to facilitate stopping the forward feeding movement at any time it is desired and thereby deenergizing the solenoid 37 so that the released compression of the spring 35 will shift the control valve into the position illustrated in the drawings thereby causing the wheel slide 10 and the grinding wheel 11 to move to a rearward or inoperative position. A manually operable control lever 43 is pivotally supported on a stud 44 which is preferably supported in fixed relationship with the base 9. The control lever 43 serves to facilitate manual actuation of the switches 41 and 42. It will be readily apparent from the foregoing disclosure that when the control lever 43 is rocked in a counter clockwise direction, the starter switch 41 will be closed to initiate a forward feeding movement. Similarly, if the control lever 43 is

rocked in a clockwise direction, the stop switch 42 will be opened so as to deenergize the relay switch 45 and thus cause the control valve to shift to cause the wheel slide 10 and grinding wheel 11 to move to an inoperative position.

A dash pot feed regulator 58 is provided for reducing the rapid approaching movement of the grinding wheel to a slow uniform grinding feed when the grinding wheel reaches a predetermined position. This regulator comprises a pair of dash pot pistons 51 and 52 arranged on diametrically opposite sides of the piston rod 18. This dash pot feed regulator is substantially the same as that shown in the prior U. S. Patent to W. H. Wood, No. 2,082,728, dated June 11, 1937, to which reference may be had for details of disclosure not contained herein. The dash pot pistons 51 and 52 are normally urged in a right hand direction by a pair of compression springs 53 and 54 which serve to return the dash pot pistons 51 and 52 to inoperative positions when the grinding wheel 11 is moved rearwardly to its inoperative position. A flanged collar 55 is adjustably mounted on a rearwardly extending portion 56 of the piston rod 18.

The rapid approaching movement of the grinding wheel 11 continues until the flanged collar 55 engages the ends of the dash pot pistons 51 and 52 and moves them toward the left. This movement serves to exhaust fluid from the dash pot cylinder chambers through a passage 57 and through a needle valve 58. By regulating the needle valve 58, the exhaust of fluid from the dash pot cylinders may be regulated so as to produce the desired feed.

Fluid exhausting through the needle valve 58 passes through a pipe 59 and through a throttle valve 60 and a pipe 61 which returns the exhausting fluid to the reservoir 25. In certain types of grinding operations it is desirable to provide not only a rapid approaching but also a slow shoulder grinding feed and then a slower uniform feed during the grinding of the peripheral body portion of a work piece. In order to provide the desired control of the exhausting fluid so as to obtain the different feeds desired, a normally open solenoid valve 63 is provided comprising a valve chamber 62. Fluid passing through the pipe 59 may pass through the chamber 62 and out through a pipe 64, through a second throttle valve 65 and through the pipe 61 into the reservoir 25. A compression spring 66 serves normally to maintain the valve in an open position. A solenoid 67 is provided which, when energized, causes an upward movement of the valve parts to close the valve and thereby to prevent fluid passing from the pipe 59 through the pipe 64.

As illustrated in the drawings, the shoulder grinding feed is determined by the setting of the needle valve 58, the throttle valves 60 and 65. When it is desired to change from a shoulder grinding feed to a body grinding feed, the solenoid 67 is energized to close the valve 63 so that fluid exhausting from the feed regulator 58 through the pipe 59 may pass only through the throttle valve 60. The throttle valve 65 being cut off by the closing of the solenoid valve 63. By manipulation of the throttle valve 60, the desired and predetermined body grinding feed may be obtained.

In order to refill the dash pot cylinders during the rearward movement of the grinding wheel 11 so that the feed regulator will be in condition for the next grinding operation, a pipe 68 is con-

nected with the pipe 19 to pass fluid to a check valve 69, through a pipe 70 into the pipe 59. It will be readily apparent from the foregoing disclosure that in the position of the valves as shown in the drawing, fluid under pressure passing through the pipe 19 will pass through the pipe 68, through the check valve 69, the pipe 70, the pipe 59, through the needle valve 58, the passage 57 into the dash pot cylinders to positively move the dash pot pistons 51 and 52 toward the right and at the same time serving to fill the dash pot cylinder chambers for the next infeeding operation.

In order to provide an extremely efficient wheel feeding mechanism, it is desirable that the solenoid valve 63 be automatically closed when the grinding wheel 11 is about to engage the work piece 12 automatically to change from a shoulder to a body grinding feed. Due to the fact that the initial size of the work pieces to be ground frequently varies, it is desirable to provide a suitable mechanism whereby the shift from shoulder to body feed occurs when the wheel 11 engages the periphery of the work piece 12 regardless of the initial size of the work piece 12. In the preferred construction, a work engaging feeler actuated mechanism is provided for controlling the shifting of the feeding mechanism. This preferably comprises a pivotally mounted feeler arm 75 which is adjustable mounted on a rock shaft 76. The rock shaft 76 is supported by a bracket 77 on a conventional type work table 18. The feeler arm 78 is provided with a work engaging roller 79. A compression spring 80 is provided for normally maintaining the roller 79 in operative engagement with the work piece 12 to be ground. A clamping screw 81 is provided to facilitate adjustment of the feeler arm 75 relative to the rock shaft 76 in setting up the machine for a given grinding operation. The rock shaft 76 also supports a rock arm 82. The rock arm 82 is preferably pinned to the shaft so that the feeler arm 75 and the rock arm 82 when adjusted act as a bell crank lever. The left hand end of the rock arm 82 supports a normally open limit switch 83 having an actuating plunger 84. The limit switch 83 is electrically connected so that when closed, it serves to energize the solenoid 67 and thereby close the solenoid valve 63.

A suitable fluid pressure mechanism is provided for controlling the actuation of the limit switch 83. This mechanism comprises a normally closed solenoid valve 85. The valve 85 is normally held in a closed position by means of a compression spring and is automatically opened by the energization of a solenoid 86. When the control valve 29 is shifted to cause a forward feeding movement of the grinding wheel 11, fluid under pressure is passed through the pipe 22 and also through a pipe 87 to convey fluid to the solenoid valve 85. When the starter switch 41 is closed to initiate a forward movement of the grinding wheel, the energizing of the relay switch 45 serves not only to energize the solenoid 37 but also to energize the solenoid 86 and thereby to open the solenoid valve 85. In this position of the valve 85, fluid under pressure passing through the pipe 87 passes through the valve 85 and through a pipe 88 to a cylinder chamber 89 formed at the lower end of a cylinder 90. The cylinder 90 contains a slidably mounted piston 91 which is connected to the lower end of a piston rod 92. The cylinder 90 and the piston rod 92 are arranged in axial alignment with the actuating plunger 84 of the limit switch 83 so that when the piston rod 92 moves

upwardly, it will engage and actuate the plunger 84 and thereby close the normally open limit switch 83.

During the upward movement of the piston 91, fluid within a cylinder chamber 93 may pass down through a pipe 94, through a throttle valve 95, through a pipe 96 which connects with pipe 19. When the control valve 29 is in a forward feeding position, the pipe 19 is connected to exhaust fluid through pipe 38. It will be readily apparent from the foregoing disclosure that the rate of movement of the piston 91 and the piston rod 92 may be readily controlled and governed by the setting of the throttle valve 95. This valve 95 is preferably adjusted so that the piston rod 92 will move upwardly and engage the plunger 84 and close the limit switch 83 when the grinding wheel 11 is about to engage the peripheral body portion of the work piece 12. It will be readily apparent that regardless of the initial diameter or size of the work piece 12, the feeler roller 79 will position the limit switch 83 so that the change from shoulder to a body feed will occur when the wheel reaches the same identical position relative to the work periphery.

In order to return the piston 91 to its downward or initial position, the pipe 96 is connected through a check valve 97 with the pipe 94 so that when fluid under pressure is admitted through the pipe 88, it may bypass the throttle valve 95 and pass directly through the pipe 94 rapidly to fill the cylinder chamber 93 and return the piston 91 to its rearward or inoperative position.

It is desirable to deenergize the solenoid 86 when the wheel slide 10 reaches or approaches its rearward position. This is preferably accomplished by providing a normally closed limit switch 98. This switch is preferably located on or fixedly mounted relative to the base 9 of the machine. The rearwardly extending portion 56 of the piston rod 18 is provided with an adjustably positioned block having a cam surface 100 which is arranged to engage an actuating roller 99 of the limit switch 98 when the wheel slide 10 approaches its rearward position to open the switch 98 and thereby to deenergize the solenoid 86 thus releasing the compression of the spring to close the solenoid valve 85.

The operation of this improved feed mechanism will be readily apparent from the foregoing disclosure. Assuming the parts to have been previously adjusted, a work piece 12 is mounted in an operative position on the machine after which the control lever 43 is rocked in a counter clockwise direction to close the starter switch 41. The closing of the switch 41 serves to energize the relay switch 45 which in turn serves to energize the solenoid 37 to shift control valve 29 so as to cause a forward feeding movement of the grinding wheel 11 and at the same time to energize the solenoid 86 to open the solenoid valve 85 so that fluid under pressure passes to the cylinder chamber 91. The grinding wheel 11 and its supporting slide 10 move rapidly to position the wheel adjacent to a shoulder portion on the work piece to be ground. The flanged member 58 is preferably adjusted so that the flanged portion engages and moves the dashpot pistons 51 and 52 thus slowing down the rapid approaching movement caused by the piston 17 to a predetermined shoulder feed as governed by the needle valve 58 and the throttle valves 60 and 65. The shoulder grinding feed continues until the wheel 11 is about to engage the peripheral portion of the work 12 at which time the piston rod 92 moving

in an upward direction engages and moves the actuating plunger 84 to close the normally open limit switch 83 thereby energizing the solenoid 67 to close the solenoid valve 83 thus cutting out the throttle valve 85 so that a body grinding feed governed by the needle valve 58 and the throttle valve 66 is automatically obtained as the wheel moves into engagement with the peripheral body portion of the work to be ground. It will be readily apparent from the foregoing disclosure that the change to a body feed occurs automatically as the wheel engages the work regardless of the initial diameter of the work piece to be ground.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:

1. In a grinding machine having a rotatable grinding wheel, a transversely movable slide therefor, and a feeding mechanism for said slide to feed said slide rapidly toward and from a work piece to be ground, means to slow down the rapid approaching feed to a predetermined grinding feed to grind a shoulder on a work piece, and means including a work engaging feeler engageable with the work piece to be ground automatically to slow down the grinding feed to a slower predetermined grinding feed when the grinding wheel engages the peripheral portion of the work to be ground.

2. In a grinding machine having a rotatable grinding wheel, a transversely movable slide therefor, and a feeding mechanism for said slide including a fluid pressure piston and cylinder to feed said slide rapidly toward and from a work piece to be ground, means to slow down the rapid approaching feed to a predetermined grinding feed to grind a shoulder on a work piece, a work engaging feeler engageable with the work piece to be ground, and means including a control device movable with said feeler automatically to slow down the grinding feed to a slower predetermined grinding feed when the grinding wheel engages the peripheral portion of the work piece to be ground.

3. In a grinding machine having a rotatable grinding wheel, a transversely movable slide for said wheel, and a feeding mechanism therefor including a piston and cylinder to feed said slide rapidly toward and away from a work piece to be ground, means including a dash pot feed regulator to slow down the rapid approaching to a predetermined grinding feed, a work engaging feeler engageable with the periphery of the work piece to be ground, and means including a limit switch movable with said feeler automatically to slow down the grinding feed to a slower predetermined grinding feed when the grinding wheel engages the peripheral surface of the work to be ground irrespective of the initial diameter of the work piece to be ground.

4. In a grinding machine having a rotatable grinding wheel, a transversely movable slide therefor, and a wheel feeding mechanism including a hydraulic piston and cylinder to move said slide rapidly toward and from a work piece to be

ground, a dash pot feed regulator which is arranged to reduce the rapid approaching movement to a predetermined shoulder grinding feed, a throttle valve to control the rate of exhaust from said regulator, a second throttle valve which is connected in parallel with the first throttle valve, said throttle valves serving to facilitate adjustment of said shoulder grinding feed, a solenoid valve which is arranged when closed to render the second throttle valve inoperative so that the first throttle valve controls exhaust from said regulator, and control means including a work engaging feeler to close said solenoid valve when the grinding wheel is about to engage the peripheral surface of the work piece regardless of the initial size thereof automatically to reduce the shoulder grinding feed to a predetermined body feed.

5. In a grinding machine having a rotatable grinding wheel, a transversely movable slide therefor, and a feeding mechanism to feed said slide rapidly toward and from a work piece to be ground, means to slow down the rapid approaching feed to a predetermined shoulder feed, 20 a movable work engaging feeler, a limit switch movable with said feeler, and means including a time delay mechanism for actuating said limit switch after a predetermined time interval automatically to slow down the shoulder grinding feed to a predetermined body feed when the grinding wheel engages the periphery of the work to be ground irrespective of the initial diameter of the work.

6. In a grinding machine having a rotatable grinding wheel, a transversely movable slide therefor, and a feeding mechanism for said slide to feed said slide rapidly toward and from a work piece to be ground, means to slow down the rapid approaching feed to a shoulder grinding feed, a 30 work engageable feeler, a limit switch which is supported to move with said feeler, an adjustable time delay mechanism to actuate said limit switch, means actuated by and in timed relation with the infeeding movement of said wheel slide to set said time delay mechanism in motion, and means actuated by said limit switch automatically to slow down the shoulder grinding feed to a slower predetermined body feed when the grinding wheel engages the periphery of the work to be ground irrespective of the initial size of the work.

7. In a grinding machine having a rotatable grinding wheel, a transversely movable slide therefor, and a feeding mechanism for said slide to feed said slide toward and from a work piece to be ground, means to slow down the rapid approaching feed to a shoulder grinding feed, a pivotally mounted work engaging feeler normally engageable with the periphery of the work piece to be ground, a limit switch mounted to move with said feeler, a hydraulically actuated time delay mechanism including a piston and cylinder operatively connected to actuate said limit switch, means including a solenoid valve to admit fluid under pressure to said timing cylinder when a forward feed of the grinding wheel is initiated, a throttle valve to control the rate of movement of said time piston so as to facilitate actuation of said limit switch, and means including a solenoid valve actuated by said limit switch automatically to slow down the shoulder feed to a slower predetermined body feed when the grinding wheel engages the periphery of the work to be ground.

8. In a grinding machine having a rotatable grinding wheel, a transversely movable slide

therefor, and a feeding mechanism for said slide to feed said slide rapidly toward and from a work piece to be ground, means to slow down the rapid approaching feed to a predetermined shoulder grinding feed, a pivotally mounted feeler normally engageable with the periphery of the work piece to be ground, a limit switch mounted to move with said feeler, a hydraulically operated time delay mechanism including a piston and cylinder arranged to actuate said feeler switch after a predetermined time interval, a solenoid valve to control the starting of said time delay mechanism, a limit switch actuated by and in timed relation with the infeeding movement of said slide to actuate said solenoid valve and thereby to start said time delay mechanism, and means including a solenoid valve actuated by said feeler switch automatically to change the wheel slide feeding movement to a predetermined body feed.

as the grinding wheel engages the peripheral portion of the work piece to be ground irrespective of the initial diameter of the work piece.
